UNITED STATES PATENT OFFICE.

CHARLES HANSEN, OF SAN JOSE, CALIFORNIA.

PHONOGRAPH.

1,379,338.

Specification of Letters Patent. Patented May 24, 1921.

Application filed June 28, 1920. Serial No. 392,319.

To all whom it may concern:

Be it known that I, CHARLES HANSEN, a citizen of the United States, and resident of San Jose, in the county of Santa Clara and 5 State of California, have invented certain new and useful Improvements in Phonographs, of which the following is a specification.

My invention relates to new and useful 10 means for reproducing sounds.

It is the object of my invention to provide a machine of the character indicated in which the recording or reproducing mechanism is embodied in one simple structure 15 positioned over the record, that is, in which the one structure embodies the sound reproducer, conveyer and distributor. It is a further object of my invention to provide a structure of the character indicated that can 20 be readily adapted for use on any type of record, that will be economical to manufacture, durable, simple in structure and mode of operation, highly efficient in its practical application, and that will more equally dis- 25 tribute sound than those forms requiring the use of a horn.

In the drawing:—

Figure 1 is a side elevation of a phonograph embodying my invention, part being 30 broken away.

Fig. 2 is a perspective view of the elemental structure embodying the simplest form of my invention.

Fig. 3 is a perspective view of another 35 elemental structure embodying a more advanced form of my invention.

Fig. 4 is a perspective view of another elemental structure embodying a still more advanced form of my invention.

40 Fig. 5 is a detail elevation of the catch used for holding the device in an inoperative position.

Fig. 6 is a top plan view of the structure 45 embodying an advanced form of my invention.

Fig. 7 is a side elevation of the device shown in Fig. 6.

Fig. 8 is a front elevation of the same.

Fig. 9 is an enlarged detail showing the 50 needle mounting.

Referring more particularly to the drawing, 1 indicates a phonograph case fitted with top 2 hinged at 3 and held open by jointed brace 4. A motor is indicated form- 55 ally at 5 operating a plate 6 through belt 7

and pulley 8, a circular disk record being shown in position on plate 6 at 9 and revolving therewith.

At 10 is shown an arm of suitable sound wave conducting material such as light, dry, 60 well seasoned wood, extending from a point in a line extending crosswise of record 9 and through the axis thereof to a point beyond the rear edge of said record. The forward end of arm 10 is fitted with a suitable socket 11 to receive a needle 12, and its upper edge is supplied with a ball 13 to engage, when raised, a socket 14 secured to the inner surface of top 2 so that the member may be held out of the way while records 70 are being changed.

Arm 10 has a cross member 15 secured to its rear end, the same being wider than arm 10 and extending both above and below the same, the lower edge of member 15 having a 75 forwardly extending shelf-like member 16 secured thereto as shown.

Secured to the upper edge of arm 10 and spaced a distance from member 15 is a wide, 80 flat, thin member 17 extending equal distances on both sides of arm 10 and forming vibrating wings. At 18—18 are shown webs secured to the under sides of wings 17 and depending therefrom in parallel relation to arm 10, each web supporting a plate 19 in 85 parallel relation to wings 18 and spaced a distance from arm 10 and members 15 and 16. These webs 18 are preferably provided with openings as at 20 to reduce the points of contact with the wings 15. 90

In the construction described the several parts are secured firmly together by any suitable means as by screws or gluing, the upper edge of arm 10 being grooved as at 21 in the present case in order to provide a 95 firm seat for member 17. Upon the central part of the rear surface of member 15 is bolted a vertically arranged socket member 22 engaging a pin 23 on horizontal hinge 24, the latter being mounted to revolve on pin 25 secured to casing 1 by bracket 26. The arm 10 and parts connected thereto may be swung upwardly on pin 23 and secured in an inoperative position by ball 13 engaging socket 14, and it may work 100 laterally over the record 9 by swinging on pivot 23.

The several members 10—15—16—17—18—19 may be made of any suitable material for the purpose disclosed and of any 110

desired proportions, areas or design according to the result desired. For instance in Fig. 2 is shown member 17 mounted on arm 10, the needle 12 being in position but the 5 mounting of the device on the phonograph case 1 being omitted for the purpose of simplifying the drawing. In this very simple construction a definite, clear but somewhat faint reproduction of the sounds recorded 10 on the record is produced, the volume being somewhat enhanced by the addition of member 15 as shown in Fig. 3, and still further increased by the addition of member 16 as shown in Fig. 4. When in addition to these 15 members 15 and 16 the members 18 and 19 are added then a volume of sound is secured that is substantially equal to that of the ordinary phonograph as usually played without a mute.

20 In addition to the extreme cheapness of construction and its accuracy in reproducing recorded sounds, the machine effects a more equal distribution of sound than is possible with a horn, the sounds reproduced 25 being thrown off laterally as well as forwardly and therefore being fully as distinct at any point to the side of the machine as at the front thereof. This construction also effectually eliminates the harsh blast of 30 sound that frequently results from discharging the sound waves through a confined space as in a horn.

In the embodiment here illustrated the 35 member 11 is made sufficiently wide to divide the space under member 17 into two distinct parts, and the members 19 are suspended in these spaces with freely vibrating edges, the members 10 and 18 preferably 40 having greater width than thickness and members 15 and 16 being of substantially 45 the same length as the width of member 17.

The socket 12 is also shown as being hollow with thin metal walls as this construction appears to improve the reproducing 45 qualities of the invention.

It is understood of course that while I have herein shown and described one particular embodiment of my invention and several modified forms thereof, this embodiment and the modified forms are to be considered as illustrative only, and that changes in form, proportions and relative arrangement of parts, members and features may be made within the scope of the appended 50 claims. While excellent results have been secured by the use of dry brittle redwood it is to be understood that any suitable material having the requisite characteristics 55 may be used.

60 I claim:

1. A device of the character indicated including a vibrating arm arranged in a vertical plane, a record engaging point operatively mounted in one end thereof, means for mounting said arm and point in opera-

tive relation to a record, and a wing-like member mounted on said arm and extending laterally therefrom.

2. A device of the character indicated including a vibrating arm arranged in a vertical plane, a record engaging point operatively mounted on one end thereof, means for mounting said arm and point in operative relation to a record, and a wing-like member mounted on said arm and extending laterally therefrom and substantially equal 75 distances on both sides thereof.

3. A device of the character indicated including a vibrating arm, a record engaging point operatively mounted on one end thereof, means for mounting said arm and point in operative relation to a record, a wing-like member mounted on said arm and extending laterally therefrom, and a second member mounted on the other end of said arm at 80 substantially right angles thereto.

4. A device of the character indicated including a vibrating arm, a record engaging point operatively mounted on one end thereof, means for mounting said arm and point in operative relation to a record, a wing-like member mounted on said arm and extending laterally therefrom, and a second member mounted on the other end of said arm at 90 substantially right angles thereto and spaced 95 a distance from said wing-like member.

5. A device of the character indicated including a vibrating arm, a record engaging point operatively mounted on one end thereof, means for mounting said arm and point 100 in operative relation to a record, a wing-like member mounted on said arm and extending laterally therefrom, and a second member mounted on the other end of said arm at 105 substantially right angles thereto, of greater width than thickness and spaced a distance from said wing-like member.

6. A device of the character indicated including a vibrating arm, a record engaging point operatively mounted on one end thereof, means for mounting said arm and point in operative relation to a record, a wing-like member mounted on said arm and extending laterally therefrom, and a second member mounted on the other end of said 110 arm at substantially right angles thereto and extending above and below said arm, of greater width than thickness and spaced a distance from said wing-like member.

7. A device of the character indicated including a vibrating arm, a record engaging point operatively mounted on one end thereof, means for mounting said arm and point in operative relation to a record, a wing-like member mounted on said arm and extending laterally therefrom, and a second member mounted on the other end of said arm at substantially right angles thereto and having a length substantially equal to the width of said wing-like member. 125 130

8. A device of the character indicated including a vibrating arm of greater width than thickness, a record engaging point operatively mounted on one end thereof, means for mounting said arm edge-wise with said point in operative relation to a record, a wing-like member mounted on the upper portion of said arm and intermediate the ends thereof and extending laterally a distance on both sides thereof and at substantially right angles thereto, and a second member of greater width than thickness mounted upon the other end of said arm, extending a distance below the same and spaced a distance from said wing-like member.
9. A device of the character indicated including a vibrating arm, a record engaging point operatively mounted on one end thereof, means for mounting said arm and point in operative relation to a record, a wing-like member mounted on said arm and extending laterally therefrom, a second member mounted on the other end of said arm at substantially right angles thereto, and a third member mounted on said second member and extending forwardly therefrom.
10. A device of the character indicated including a vibrating arm, a record engaging point operatively mounted on one end thereof, means for mounting said arm and point in operative relation to a record, a wing-like member mounted on said arm and extending laterally therefrom, a second member mounted on the other end of said arm at substantially right angles thereto, and a third member mounted on said second member and extending forwardly therefrom and spaced a distance below the lower edge of said arm.
11. A device of the character indicated including a vibrating arm adapted to have a record engaging point operatively mounted on one end thereof, means for mounting said arm in operative relation to a record, a wing-like member mounted on the upper portion of said arm and intermediate the ends thereof and extending laterally a distance on both sides thereof, a second member mounted upon the other end of said arm in substantially parallel relation to said wing-like member and extending therebelow, and a plate supported in substantially parallel relation to said wing-like member on each side of said arm and spaced a distance from said arm and said second member.
12. A device of the character indicated including a vibrating arm adapted to have a record engaging point operatively mounted on one end thereof, means for mounting said arm in operative relation to a record, a wing-like member mounted on the upper portion of said arm and intermediate the ends thereof and extending laterally a distance on both sides thereof and extending laterally a distance on both sides thereof, and a plate supported in substantially parallel relation to said wing-like member on each side of said arm and spaced a distance from said arm and said second member.
13. A device of the character indicated including a vibrating arm adapted to have a record engaging point operatively mounted on one end thereof, means for mounting said arm in operative relation to a record, a wing-like member mounted on the upper portion of said arm and intermediate the ends thereof and extending laterally a distance on both sides thereof, a second member mounted upon the other end of said arm in substantially parallel relation to said wing-like member and extending therebelow, a third member mounted on said second member, extending forwardly therefrom, and spaced a distance below said arm, and a plate supported in substantially parallel relation to said wing-like member on each side of said arm and spaced a distance from said arm and said second member.
14. A device of the character indicated including a vibrating arm adapted to have a record engaging point operatively mounted on one end thereof, means for mounting said arm in operative relation to a record, a wing-like member mounted on the upper portion of said arm and intermediate the ends thereof, a second member mounted upon the other end of said arm in substantially parallel relation to said wing-like member and extending therebelow, a web member mounted edge-wise upon the under side of each laterally extending portion of said wing-like member and in substantially the center thereof, and a plate mounted upon the lower portion of each web member in substantially parallel relation to said wing-like member and spaced a distance from said arm and said second member.
15. A device of the character indicated including a vibrating arm adapted to have a record engaging point operatively mounted on one end thereof, means for mounting said arm in operative relation to a record, a wing-like member mounted on the upper portion of said arm and intermediate the ends thereof and extending laterally a distance on both sides thereof, a second member mounted upon the other end of said arm in substantially parallel relation to said wing-like member and extending therebelow, a web member having an opening formed therein mounted edgewise upon the under side of each laterally extending portion of said wing-like member and in substantially the center thereof, and a plate mounted upon the lower portion of each web member in substantially parallel relation to said wing-like member and spaced a distance from said arm and said second member.
